UNITED STATES PATENT OFFICE.

LOUIS K. VAUGHN, OF WOODLAND, CALIFORNIA.

NUT HULLING AND CRACKING MACHINE.

1,294,852.

Specification of Letters Patent. Patented Feb. 18, 1919.

Application filed February 21, 1917. Serial No. 150,604.

To all whom it may concern:

Be it known that I, LOUIS K. VAUGHN, a citizen of the United States, residing at Woodland, in the county of Yolo and State 5 of California, have invented a new and useful Improvement in Nut Hulling and Cracking Machines, of which the following is a specification.

My invention relates to nut hulling and 10 cracking machines wherein a hull and shell cracking mechanism operates in conjunction with a pair of screens; and the objects of my invention are—

First, to provide improved means adapted 15 to separate hulls from almond nuts and the like;

Second, to provide an improved machine 20 of the character described which shall also be adapted to crack the shells of hulled almond nuts and the like and to separate the kernels from the shells;

Third, to provide an improved nut hulling and cracking machine having adjustable means whereby the said machine may be 25 used for either cracking or hulling;

Fourth, to provide improved means for returning unhulled or unshelled nuts through the machine; and

Fifth, to provide an improved adjustable 30 attrition element to remove the hulls or shells from almond nuts.

I accomplish these several objects by means of the preferred form of the device disclosed in the drawings forming a part of the present specification wherein like characters of reference are used to designate similar parts throughout the said specification and drawings, and in which—

Figure 1 is a broken side elevation of the 40 machine.

Fig. 2 is a broken plan view of Fig. 1 with the upper hopper removed and portions of the screens broken away in order to disclose matter lying thereunder.

Fig. 3 is an enlarged broken vertical section of the cracking and feeding mechanism.

Fig. 4 is a transverse sectional view through the screens and the frame of the machine disclosing the means for adjusting 50 the movable screen;

Fig. 5 is an elevation of one end of the machine disclosing the mechanism for adjusting the tension of the upper screen and the delivery chutes from the lower screen; 55 and

Fig. 6 is a transverse sectional view on an

enlarged scale taken through the draper and grading compartments.

Referring to the drawings the numeral 1 is used to designate a suitable frame in the upper portion of which is suspended a substantially stationary inclined screen 2 suspended at its upper end by means of a hinge 3 and at its lower end by means of a yielding support composed of a threaded stem 4 threaded into a transverse bar 6 which is a portion of the frame 1. The lower end of the threaded stem 4 is rotatably mounted in a bar 7 slidably mounted between two upright or vertical members of the frame 1. A second bar 8 is suspended from the first bar 7 by means of bolts 9 provided with thumb nuts 11 by means of which the said bar 8 may be raised and springs 12 are interposed between the two bars to resiliently resist an upward movement of the lower end of the screen 2.

The tension of the springs 12 may be regulated by means of the bolts 9 and nuts 11 the purpose of which will hereinafter be more fully set forth.

A movable screen 14 is provided with transverse bars 16 and a lower screen 17 and is slidably mounted within the frame 1 by being mounted upon rollers 18 which may be raised or lowered to adjust the space between said lower screen 14 and the upper screen 2, with which it is arranged in substantially parallel relation, by means of threaded stems 19 mounted within brackets 21.

A reciprocating movement or motion is imparted to the movable screen 14 by means of a connecting rod 22 which connects said screen 14 with a rotating head 23.

At the upper ends of both screens 2 and 14 is a corrugated roller 26 rotatably mounted within the frame 1 and directly below a hopper 27 which feeds nuts to be hulled or cracked to the said roller 26.

A corrugated arcuate member 28 is pivotally mounted as at 29 and is arranged substantially concentric with the roller 26 and spaced apart therefrom and said space is adjusted by means of an adjusting screw 31.

The lower or movable screen 14 is also provided with a screen 17 arranged below the bars 16 to prevent the passage and thereby retain nut kernels which may pass through the bars 16 and deliver said kernels to an inclined chute 33 at the lower end of the screens 2 and 14.

A second oppositely inclined chute 34 at the

lower ends of the screens 2 and 14 receive nuts or kernels from the lower ends of the said screens and delivers the same onto a draper 36 above or on which are arranged several grading compartments 37, 38 and 39.

The outermost grading compartment 37 delivers unhulled or unshelled nuts to a hopper 41 from which rises a conveyer 42 to convey nuts to the upper hopper 27 above the cracking and feeding roller 26.

The conveyer 42 is operated from the draper drive shaft 43 by means of a gear 44 thereon which meshes with a gear 45 on the lower conveyer shaft 46.

15 The shaft 46 is also provided with a pulley 47 from which a drive belt 48 runs to a sheave or pulley 49 to a shaft 50 upon the other end of which is mounted the rotating disk or head 23 which operates or reciprocates the lower or movable screen 14.

16 The shaft 50 is also provided with a gear 51 which meshes with and drives a gear 52 on the shaft 53 of the rotating corrugated roller 26.

25 The operation is as follows:

The nuts are of the almond or any other similar husk type of nut where it is desired to first remove the husk or hull and then crack the nuts and remove the kernels therefrom.

30 The nuts are first introduced into the lower hopper 41 from whence they are conveyed by means of the conveyer 42 to the upper hopper 27 as disclosed in Fig. 3 of the drawings.

In hulling or husking the almond nuts the space between the arcuate corrugated members 28 and the roller 26 is adjusted by means of the screw 31 to slightly crush and 40 break the hull and partly separate the same from the shell of the nut without cracking the said shell.

45 Emerging from between the lower end of the arcuate member 28 and the roller 26 the partially crushed nuts are fed between the upper and lower screens 2 and 14 respectively and the reciprocating movement or motion imparted to the lower screen 14 tends to move the nuts between the upper 50 and lower screens the space between which is slightly larger at the upper than at the lower end.

55 As the nuts are moved forward by the reciprocating movement of the lower screen 14 they are subjected to a frictional contact with the bars 16 of the lower screen 14 as well as with the upper side of the upper screen 2 and the hulls are thereby removed by attrition, said hulls dropping between 60 the transverse bars 16 and onto the screen 17 which delivers the hulls into the chute 33 as the said screen 17 is somewhat shorter on the lower end of the screen 14 than the length of the bars 16 thereon.

65 The extent of the rubbing or frictional en-

gagement of the upper screen may be adjusted by means of the threaded stem 4 which may be operated to lower the bar 7 and thereby increase the tension of the springs 12 and consequently cause a greater pressure to be exerted by the screen 2.

70 After the hulls have been removed by attrition the nuts are conveyed onto the draper 36 by the chute 34. Operators sort and cast the various grades of nuts into the several grading compartments 38 or 39, each successive compartment having a higher wall than the preceding one as disclosed in Fig. 6 of the drawings, to prevent the nuts of one grade from being easily cast 75 into the compartment of the next higher grade.

80 Any nuts that have not been properly or fully hulled are cast into the compartment 37 and are returned by means of the forward movement of the draper 37 to the lower hopper 41 from whence they are again conveyed into the feeding hopper 27 and again conveyed through the screens 2 and 14 to be again subjected to a frictional movement which second subjection generally tends to accomplish the desired result.

85 After the nuts are entirely hulled they are again run through the machine in the manner hereinbefore described but the space 23 between the arcuate member 28 and the corrugated roller 26 is lessened to an extent that will crack the shells as the nuts are forced through said space by said roller 26.

90 As the nuts with their cracked shells are fed between the screens 2 and 14 the kernels are easily separated by the reciprocating movement of the screen 14 and the frictional engagement with the upper screen 2. The kernels of the larger variety are 105 delivered over the transverse bars 16 to the chute 34 and conveyed to the draper 36 where they are graded by being cast into proper grading compartments 38 or 39 while the uncracked nuts are cast into the return 110 compartment by the operator to be returned to the lower hopper 41 and again conveyed to the upper hopper 27 and once more run through the machine.

115 The distance between the screens 2 and 14 as disclosed in Fig. 1 is somewhat larger than normal for purposes of illustration, and in actual practice this distance is regulated to a degree that will readily remove the shells and hulls without injury to the 120 kernels.

125 As the tension of the springs 12 may be regulated or adjusted by means of the threaded stem 4 it is evident that the frictional pressure of the screen 2 upon the nuts may be regulated also.

130 The details of construction are so susceptible to variation that I do not wish to confine myself to the precise construction shown herein but rather to avail myself of 130

any modification that may fall properly within the scope of my invention.

Having thus described my invention what I claim as new and desire to secure by 5 Letters Patent is—

An almond hulling mechanism including in conjunction with feeding means, a rectangular frame adapted for longitudinal reciprocating movement having its up- 10 per end positioned under the crushing means to receive the nuts therefrom, said frame slanting downward from the upper end, a plurality of spaced bars fixed to the frame transversely thereof, a stationary cover over

the frame at a spaced distance therefrom 15 such that the lower end of the cover is closer to the bars than the upper end whereby with the reciprocating movement of the frame, the nuts will move toward the lower end thereof and will come into frictional 20 contact with the cover and the bars, thereby removing the hulls from the nuts by attrition, and means whereby the lower end of the cover may be adjusted relative to the spacing thereof with the bars. 25

In witness whereof I hereunto set my signature.

LOUIS K. VAUGHN.
